UNITED STATES PATENT OFFICE.

WALTER F. VAN GUYSLING, OF ALBANY, NEW YORK.

FORCE-FEED LUBRICATOR.

1,212,715.

Specification of Letters Patent. Patented Jan. 16, 1917.

Application filed September 9, 1916. Serial No. 119,156.

To all whom it may concern:

Be it known that I, WALTER F. VAN GUYSLING, a citizen of the United States of America, and a resident of Albany, Albany 5 county, and State of New York, have invented certain new and useful Improvements in Force-Feed Lubricators, of which the following is a specification, reference being had to the accompanying drawings, forming a 10 part thereof.

My invention relates to improvements in automatic lubricators of the type in which the oil or lubricant is forcibly fed to the machine to which it is applied by the movement of the machine itself and its object is 15 to provide a simple and effective device which is adapted to supply the oil positively in variable quantities automatically regulated by the speed of the machine receiving 20 the oil.

Another object is to so arrange the parts that a new supply of oil may be put in readily and to provide a positively-acting automatic stop which will bring the device to 25 rest when the supply of lubricant is substantially exhausted.

These and other objects of the invention will appear in the following specification in which I will describe my invention, the 30 novel features of which will be set forth in appended claims.

Referring to the drawings, Figure 1 is a front elevation partly in section of an apparatus which embodies the invention. Fig. 35 2 is a sectional side elevation of a part of the same device, the section being taken on the line 2—2 of Fig. 1. Fig. 3 is a side elevation of my improved lubricator with portions broken away to more clearly illustrate 40 some of the details of its construction. Fig. 4 is a sectional plan view of the device, the section being taken on the line 4—4 of Fig. 3. Fig. 5 is a sectional plan view on a larger scale of the mechanism, the section in this 45 figure being taken on the line 5—5 of Fig. 3. Fig. 6 is a plan view of the oil container and Fig. 7 is a plan view of a screw head on which the base of the container rests. Fig. 8 is a front elevation of one of the actuating 50 pawls with its supporting parts shown in section. Fig. 9 is a detail of one of the parts, this figure being a front elevation of a replaceable bracket.

Like characters of reference designate corresponding parts in all the figures.

10 designates a frame or casting which

forms a part of the apparatus and upon which its other parts are supported. This is constructed with flanges 11 by means of which the device may be attached to the machine with which it is to be used, such for example, as a steam locomotive. This frame comprises a rectangular base 12 and two upright portions 13 which are integrally united at the top by a part 14. In the center of this 60 part 14 is a tubular member 15 to the upper end of which an oil discharge pipe may be connected, and the lower part of which is enlarged to form a piston. A cup leather 16 is held on this piston by a part 17 which is 65 threaded into the piston and this part contains a check valve 18.

The base of the frame is bored out to receive an internally-threaded collar 20, the upper part of which is enlarged to form a 70 shoulder which prevents its downward movement and under this shoulder are balls 21 which form an anti-friction bearing. A ratchet disk 22 is affixed to the lower end 75 of collar 20 which projects below the base 12 80 for the purpose of receiving it. This ratchet disk 22 is provided with handles 23 by means of which it may be manipulated.

24 is a screw, which engages the threads 85 of collar 20. The upper end of screw 24 is provided with a square flat head 25 at one corner of which is a screw 26 and at the opposite corner a slot 27.

30 is the oil chamber which is a cylindrical member, and 31 its base. This base is 90 provided with a screw 32 which fits into the slot 27 and at its opposite corner is a slot 33 into which screw 26 fits. One side of this base projects as at 34 and this projecting portion is offset as shown in Fig. 6 to form 95 a shoulder 35, the purpose of which will be fully described hereinafter.

The central portion of the frame base 12 is extended on the side opposite flanges 11 to form a lug 40 on which is supported a 100 heavy bracket 41. A heavy stud 42 and its nuts 43 serve to affix this bracket to the lug, and its protruding end serves as a bearing for the hub 44 of a ratchet disk 45 and for a pawl carrier 50. A spring wire 46 fits in a 105 groove in the periphery of the disk 45. One end of this wire is secured to a hub 47 which is the outer end of bracket 41 and the wire after encircling the disk is looped around itself in front of a button 48 between which 110 and the lug 47 is a compression spring 49 (Fig. 1). This forms an effective brake for

preventing the rotation of the disk 45 in one direction and yet allowing it to be rotated in the other direction.

The pawl carrier 50 on stud 42 has a side lug 51, to which is secured a rod 52 which is rocked about the axis of the stud 42 by a rod 53 which is connected to be reciprocated by some moving part of the engine or other apparatus to which the lubricant is to be supplied. On the rod 52 is a pawl 54 which is freely supported on the rod 52. This pawl carrier is carried up over the pawl as at 55 and a spring 56 between the pawl and the pawl carrier presses the pawl into engagement with the teeth on disk 45. The hub 44 of the disk 45 is constructed to form an eccentric on which is loosely supported another pawl 60 which engages the teeth on the top of ratchet disk 22. On the end 20 of pawl 60 is an offset projection 61 (Fig. 5). Another pawl 62 with an offset projection 63 is mounted on a pin 64 projecting through the bracket 41. This pawl also engages the teeth on the top of the ratchet disk 22.

25 70 is a vertical rod, guided between a cut out portion 71 of bracket 41 and the side of the lug 40. The lower end 72 of this rod is bent at right angles and lies under the pawl projections 61 and 63. The upper part of rod 70 passes through a slot in the bottom of a guide bracket 73 affixed to one of the frame arms 13 and its upper end 74 projects through a slot in the side of guide bracket 73 into the path of movement of the shoulder 35 of the base of the oil chamber.

30 75 is a bell crank lever which is pivoted to casing 10 at 76 and the other end of which is a weight 77. It is also provided with a lug 77^A projecting from its pivoted hub oppositely from weight 77. Pin 78 projects from the bell crank lever 75 into a loop 79 formed by a bend in the rod 70. A depression is formed between the lug 77^A of the bell crank lever and the end of its arm 75 into which is pressed a latch 80 which is slidably mounted in a lug 81 projecting from the frame 10, by means of a spring 82.

45 This apparatus may be affixed to one or the other side of a device to be lubricated, such for example as a steam locomotive, instead of making right and left hand lubricators. I have so designed the device that the bracket 41 may be removed and another one affixed to the lug 40 on the opposite side thereof. The driving parts, such as are shown in Fig. 5 may then be changed to provide for the device being driven from the opposite side so that the main parts of the apparatus may be used for either a right or left hand drive.

50 The operation of this apparatus is as follows: The ratchet disk 22 is turned by its handles 23 until its head seats on the base 65 portion 12 of frame 10. When in this posi-

tion the piston and its attached parts will be clear of the cylinder 36 and by grasping the projection 34 the oil receptacle may be removed laterally. After it is filled with oil, grease or other desired material it is slid back again into place. The screws 26 and 32 and the slots 33 and 27 with which they respectively engage, serve to position the cylindrical oil chamber in alinement with the piston 17. The square head 25 of the screw 75 and the rectangular base 31 of the oil receptacle fit upright portions 13-13 of the frame in such a way as to hold the screw 24 from turning. Now as the disk 22 and its connected nut-like collar are rotated to raise the screw 20, the cylindrical receptacle 30 is pushed up over the cup leather 16 on piston 15 and this cylinder and cup leather have an oil-tight fit. Now as the machine to which the lubricator is connected runs, and the rod 52 is rocked thereby, the pawl 54 will rotate disk 45 step by step by its engagement with the teeth on the disk. For each revolution of the disk 45 the pawl 60, on account of its being supported on the eccentric hub 44 of 90 the disk, will be moved forward and back and will impart a partial rotation to the ratchet disk 22, the amount of this rotation being dependent upon the space between the teeth on disk 22. The pawl 62 is provided 95 to prevent the disk 22 from moving backward. This will turn the nut-like collar 20 and move the screw 42 and the oil receptacle which is on it upwardly. Thus the oil will be forced out gradually at a rate proportional to that of the machine to which the lubricator is applied. The end 74 of rod 70 is in alinement with the shoulder 35 and as the oil chamber is moved upwardly this shoulder will in time engage the rod 70 and 100 force it too upwardly. The loop 79 will swing the bell-crank lever about its pivot 76 until its heavy arm 77 passes over its vertical position after which it will fall over into a position inclined in the opposite direction to 110 the incline in which it is shown in Fig. 3. In doing this it will raise the rod 70 farther and this in turn will cause its lower end 72 to engage pawl projections 61 and 63 and to raise the pawls 60 and 62 out of further engagement with the ratchet disk 22 and thereby stop further action of the threaded collar 20 on screw 24, and thus stop the discharge of lubricant. These parts are so proportioned and arranged that this automatic stopping will occur at about the time the oil in the reservoir or chamber has become exhausted.

115 It is to be noted that the movement of the bell-crank lever is opposed by the latch 80, 125 but as its movement is accomplished by the application of a considerable amount of force, this latch will be depressed until the lug 77^A passes over it. This is important as in some cases, such for example when the 130

device is applied to a locomotive, the action of the lubricator is liable to be stopped accidentally by the jarring of the locomotive, but this device positively prevents such accidental stopping.

To refill the reservoir no pipes need be disconnected but the operator simply turns the disk 22 in the direction opposite to that in which it has been driven, until the head of screw 24 abuts against the collar 20 when the oil receptacle is again in position to be removed.

The apparatus shown and described is illustrative of my invention although variations in construction may be made within the scope of the invention, and I intend no limitations other than those imposed by the appended claims.

What I claim is:

23 1. A force feed lubricator comprising a frame, a stationary piston supported thereby, an internally threaded collar in said frame arranged to be rotated by the movement of the machine to which the lubricator 25 is to be applied, a screw passing through the collar, an oil receptacle and coöperating means for holding said receptacle on said screw in alinement with said piston.

2. A force feed lubricator comprising a 30 frame, a stationary piston supported thereby, an internally threaded collar in said frame arranged to be rotated by the movement of the machine to which the lubricator is to be applied, a screw passing through the 35 collar, said screw having a head guided by the frame and arranged to prevent the screw from turning, an oil receptacle having a base, and coöperating means for holding said base and said screw head together to hold 40 the oil receptacle in alinement with said piston.

3. A force feed lubricator comprising a frame, a stationary piston supported thereby, an internally threaded collar in said 45 frame arranged to be rotated by the movement of a machine to which the lubricator is to be applied, a screw passing through the collar, said screw having a flat rectangular head, an oil receptacle having a rectangular 50 base fitting onto said screw head, a screw projecting from the screw head and a slot provided in said base for receiving said screw, a similar screw projecting from said base and a slot in screw head provided to receive 55 the latter screw, said screws and slots being arranged to hold the receptacle in alinement with said piston.

4. A force feed lubricator comprising a frame, a stationary piston supported thereby, an internally threaded collar in said 60 frame arranged to be rotated by the movement of a machine to which the lubricator is to be applied, a screw passing through the collar, said screw having a flat rectangular head, an oil receptacle having a rectangular 65

base fitting onto said screw head, a screw projecting from the screw head and a slot provided in said base for receiving said screw, a similar screw projecting from said base and a slot in screw head provided to receive the latter screw, said screws and slots being arranged to hold the receptacle in alinement with said piston, said base projecting from one side of the frame and means engaged by said projecting portion of the base for automatically stopping rotation of said collar.

5. A force feed lubricator comprising a frame, having a base portion, parallel side portions and an intermediate portion forming a stationary hollow piston, an internally threaded collar in said base portion, driving mechanism connected to rotate said collar, a screw passing through said collar, said screw having a head fitted between the parallel side portions of the frame, an oil receptacle having a base fitted between the parallel side portions of the frame, and means for attaching said receptacle to said screw head in alinement with said piston.

6. A force feed lubricator comprising a frame, having a base portion, parallel side portions and an intermediate portion forming a hollow piston, an internally threaded collar in said base portion, driving mechanism connected to rotate said collar, a screw passing through said collar, said screw having a rectangular head fitted between the parallel side portions of the frame, an oil receptacle having a rectangular projecting base guided by said frame and constructed with means for connecting it with said screw head in alinement with the piston, and means engaged by said projecting base for automatically disconnecting said driving mechanism from the collar.

7. A force feed lubricator comprising a frame, a stationary piston supported thereby, an internally threaded collar in said frame arranged to be rotated by the movement of a machine to which the lubricator is to be applied, a screw passing through the collar, an oil receptacle provided with means for securing it to the screw in alinement with the piston, means engaged by said receptacle for automatically stopping the rotation of said collar, and a yieldable lock for said stopping means.

8. A force feed lubricator comprising a frame, having a base portion, parallel side portions and an intermediate stationary portion forming a hollow piston, an internally threaded collar in said base portion, a driving mechanism connected to rotate said collar, a screw passing through said collar, an oil receptacle having a rectangular projecting base guided by said frame and constructed with means for securing the receptacle to the screw in alinement with the piston, means engaged by said projecting base

for automatically disconnecting said driving mechanism from the collar and a yieldable lock for said disconnecting means.

9. A force feed lubricator comprising a frame, having a base portion, parallel side portions and an intermediate stationary portion forming a hollow piston, an internally threaded collar in said base portion, a driving mechanism comprising a ratchet disk attached to said collar and a pawl adapted to engage said disk, a screw passing through said collar, said screw having a rectangular head guided by said frame, an oil receptacle fitting the piston and having a rectangular projecting base guided between the side portions of the frame and constructed with means for securing the receptacle to the screw head in alinement with the piston, a weighted lever having a lost motion connection with said pawl, a portion of the oil receptacle base being arranged to move said lever to disengage the pawl, and a spring pressed latch to releasably hold said lever.
- 25 10. A force feed lubricator comprising a frame, having a base portion, parallel side portions and an intermediate stationary portion forming a hollow piston, an internally threaded collar in said base portion, a driving mechanism comprising a ratchet disk attached to said collar and pawls adapted to engage said disk, means for actuating one of said pawls by the movement of a machine to which the lubricator is to be applied, a screw passing through said collar,

said screw having a head, an oil receptacle fitting said piston and having a base adapted to be secured to said screw head and to be guided between the side portions of the frame, a rod having a portion projecting into the path of movement of said oil receptacle, and another portion projecting under the pawls, and means for augmenting the movement imparted to said rod by the receptacle.

40 11. A force feed lubricator comprising a frame, having a base portion, parallel side portions and an intermediate stationary portion forming a hollow piston, an internally threaded collar in said base portion a driving mechanism comprising a ratchet disk attached to said collar and pawls adapted to engage said disk, means for actuating one of said pawls by the movement of a machine to which the lubricator is to be applied, a screw 50 passing through said collar, said screw having a head, an oil receptacle fitting said piston and having a base adapted to be secured to said screw head in alinement with the piston, and to be guided between the side portions of the frame, a weighted bell crank lever, a rod connected with said lever having a portion projecting into the path of movement of said oil receptacle base, and another portion projecting under the pawls, and a spring pressed latch to releasably hold said weighted lever.

55 In witness whereof, I have hereunto set my hand this 5 day of September, 1916.

WALTER F. VAN GUYSLING.
